UNITED STATES PATENT OFFICE.

WILLIAM B. TUNSTALL, OF MELROSE, MASSACHUSETTS, ASSIGNOR OF ONE-HALF TO COLE & TREAT CO., OF BOSTON, MASSACHUSETTS, A CORPORATION OF MASSACHUSETTS.

PNEUMATIC FOR WIND INSTRUMENTS.

No. 926,686.

Specification of Letters Patent.

Patented June 29, 1909.

Application filed May 22, 1908. Serial No. 434,261.

To all whom it may concern:

Be it known that I, WILLIAM B. TUNSTALL, a citizen of the United States, residing at Melrose, in the county of Middlesex and 5 State of Massachusetts, have invented a new and useful Pneumatic for Wind Instruments, of which the following is a specification.

This invention relates to a pneumatic and valve for wind instruments.

10 The principal objects of the invention are to provide a rigid and firm construction which can be set up and taken down in a very simple manner, and which is adapted to operate a valve for controlling an air channel 15 in an efficient and convenient manner; also to provide certain improvements in details of construction of the pneumatic and in the manner of connecting it with the instrument.

Further objects and advantages of the invention will appear hereinafter.

Reference is to be had to the accompanying drawing which shows a sectional view of a pneumatic constructed according to this invention and applied to an ordinary type of 25 organ.

The invention is illustrated as applied to an instrument having a pressure chamber 10 located adjacent to a plate 11 having a set of channels 12 connected with the pipes of the 30 instrument, and a set of channels 13 communicating with the pressure chamber through ports 14 each controlled by a valve 15. This valve is shown as being operated by a pneumatic 16 communicating with a 35 channel 17 leading from the key action. Over each channel 13 is placed a block 20 having a port 21 therethrough communicating with the channel 13. This block projects out from the face of the plate 11 a considerable distance and upon it is fixed by 40 means of screws or in any other desired manner, the stationary leaf 22 of the pneumatic which is designed to operate the valve 23 which controls the channel 12. This 45 stationary leaf is provided with a longitudinal passage 24 communicating through a port 25 with the port 21 and channel 13. The passage 24 extends out into the interior of the pneumatic and is bounded on one side by 50 a wall 26 having a slanting side 27. At the end of this slanting side nearest the plate 11 the movable leaf 28 of the pneumatic is pivoted. It will be seen that this part of the pneumatic projects inwardly toward the plate

11 in the space afforded by the location of 55 the pneumatic on the block 20. Consequently as the valve 23 is located on the outside of the movable leaf 28, and as the slanting surface 27 constitutes a stop for the inward motion of the movable leaf, it will be 60 seen that the parts are most conveniently located for performing the desired functions. They can be set up in position in a very convenient manner, and they are so constructed 65 that when put in position they are rigid and not likely to get out of order. The control of the valve 23 is perfect, and the construction by which it is brought about is most simple and inexpensive. A simple and convenient form of spring is also shown. It 70 consists of a single piece of wire 30 fixed into the back of the stationary leaf of the pneumatic, and extending around over the end of the same into a recess in the end of the movable leaf. 75

The device can be applied to suction instruments and may be used in many ways other than that shown.

The operation is as follows:—Upon the venting of the tube 17 at the key-board, the 80 pneumatic 16 is deflated, by the movement of valves 15 toward the pneumatic 16 by reason of air pressure in the chest 10, which cuts the passage 14 off from the chamber 10, and connects it with the outer air. This vents 85 the interior of the power pneumatic which is then collapsed by the pressure in the chamber 10 against the movable leaf 28.

While I have illustrated and described certain details of construction, and shown the 90 invention as applied to one type of wind instrument, I am aware that many modifications may be made therein and that it can be applied to other kinds of instruments by any person skilled in the art without departing 95 from the scope of the invention as expressed in the claims. Therefore, I do not wish to be limited to all the details of construction, or the form of instrument shown, but

What I do claim is:—

1. A pneumatic comprising a stationary leaf having at one end means for securing it in fixed position, a wall extending from said means toward the other end of the stationary leaf and provided with a surface slanting at an angle to the fixed leaf, a movable leaf pivoted at the end of said slanting surface which is most remote from the fixed leaf, whereby 100 105

said surface constitutes a stop for the movable leaf, and a passage between said wall and the stationary leaf and extending through the stationary leaf.

5 2. A valve operating pneumatic comprising a fixed leaf having a longitudinal passage therethrough communicating with the interior of the pneumatic, a movable leaf, a valve on the outside of the movable leaf, and a 10 spring connected with the end of the movable leaf and extending around the outside of the pneumatic and fixed to the opposite side of the fixed leaf.

3. In a pneumatic, the combination of a 15 stationary leaf having a longitudinal passage communicating with the interior and having a wall bounding the inner side of said passage at one end and provided with an outer face at an angle to the stationary leaf, and a movable leaf pivoted to the edge of said outer 20

face, whereby said wall acts as a support and as a stop for the movable leaf.

4. In a pneumatic musical instrument, the combination of a pressure chamber, a pneumatic therein having a longitudinal passage, 25 a channel communicating with said passage and also communicating with said pressure chamber, a valve in said chamber for controlling said channel, a second channel normally communicating with said pressure 30 chamber, said pneumatic having a movable leaf, and a valve for closing the second channel controlled by said movable leaf.

In testimony whereof I have hereunto set my hand, in the presence of two subscribing 35 witnesses.

WILLIAM B. TUNSTALL.
